UNITED STATES PATENT OFFICE.

GEORGE P. FITZSIMMONS, OF NEWARK, NEW JERSEY.

ENVELOP.

1,148,671.

Specification of Letters Patent.

Patented Aug. 3, 1915.

Application filed September 30, 1914. Serial No. 864,206.

To all whom it may concern:

Be it known that I, GEORGE P. FITZSIMMONS, a citizen of the United States, residing at Newark, in the county of Essex and State of New Jersey, have invented certain new and useful Improvements in Envelops; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in envelopes; and, the present invention has reference, more particularly, to a novel form of envelop for inclosing letters or papers, the envelop having the same appearance, in general, as the ordinary envelopes, but the surrounding marginal edges of the envelop being in the form of narrow squared sides at right angles to the front and back of the envelop, so as to provide an increased receiving space for readily receiving the contents, and, furthermore, to more easily permit of the removal of the contents.

In connection with an envelop of the general character above stated and hereinafter more particularly specified, the invention has reference, also, to the provision of means, in the form of a tearing strip, which is secured upon the inner surface of one of the said right angled edge-sides, for the removal of such edge-side when it is desired to get at the contents of the sealed envelop.

The present invention, therefore, has for its principal objects, first, to provide an envelop having such squared or right-angled edge-sides, to increase the receiving space of the envelop; and secondly, to provide an envelop of the character stated with a tearing strip within the envelop and upon the inner face of one of said edge-sides for readily removing the entire edge-side, without mutilation of the parts of the envelop at the opening.

The invention has for its further object to provide an envelop of the character stated which may be easily and cheaply manufactured, the tearing or severing means thereof being capable of incorporation with the envelop during the manufacture of the envelop, and to extend one end of the tearing strip through a slit at one of the cor-

ners of the envelop so as to provide a means which may be readily grasped, to pull the said tearing strip against the right-angled or squared edge-side of the envelop, to sever the said edge-side along its two marginal edges where it is joined, respectively, to the front and to the back of the envelop.

Other objects of this invention not at this time more particularly enumerated will be clearly understood from the following detailed description of the present invention.

With the various objects of the present invention in view, the invention consists, primarily, in the novel envelop hereinafter set forth; and the invention consists, furthermore, in the novel arrangements and combinations of the several parts, all of which will be more fully described in the following specification, and then finally embodied in the clauses of the claim which are appended to and which form an essential part of this specification.

The invention is clearly illustrated in the accompanying drawings, in which:

Figure 1 is a rear face view of an envelop made according to and embodying the principles of the present invention, and Fig. 2 is an end-edge view of the same, looking in the direction of the arrow α in said Fig. 1. Fig. 3 is a rear face view of the envelop, similar to that represented in said Fig. 1, but showing more particularly the manner of severing the end-edge of the envelop; and Fig. 4 is a detail horizontal sectional representation taken on line 4-4 in said Fig. 1. Fig. 5 is a view of the blank from which the improved envelop is manufactured.

Similar characters of reference are employed in all of the above described views, to indicate corresponding parts.

Referring now to the several figures of the drawings, the reference-character 1 indicates the body of the envelop, 2 the lower flap, 3 the sealing flap, and 4 the end flaps.

As indicated by the dotted lines 5 and 6, shown in Fig. 5 of the drawings, the various flaps 2, 3 and 4 are respectively connected with the body 1 by the narrow portions 7, one of the said narrow portions 7 being preferably cut away, as at 8, between the one end flap 4 and the body 1, as illustrated in said Fig. 5 for the purposes to be presently more fully set forth.

During the manufacture of the envelop, the blank represented in said Fig. 5 is folded upon the several dotted lines 5 and 6, where-

by an envelop is provided which is formed at the top, at the bottom, and at the ends, with squared or right-angled edge-sides 9, as shown in Figs. 2 and 4 of the drawings. 5 The tearing or severing means hereinabove mentioned, and shown in Figs. 1 to 4 inclusive, consists essentially of a single strip 10 of substantially the same width as the narrow portion 7, the said strip 10 being se- 10 curely pasted, or otherwise secured upon the inner surface of one of the said squared or right-angled edge-sides 9, the said strip be- 15 ing of such length that it will cover the entire inner surface of the said edge-side, and that its free end-portion 11 will project from the previously mentioned cut away part 8, to provide a suitable fingerpiece or grasping 20 means for taking hold of the tearing strip and thereby easily severing the squared or right-angled edge-side 10 from its connection 25 with the sealed envelop, and thus provide an enlarged and non-mutilated end-opening for the easy removal of the contents of the envelop, as will be clearly evident, the parted or severed portion being torn away upon straight lines, leaving no unduly 30 ragged edges and with the back of the envelop, formed by the several sealed flaps, left in its entirety. The said tearing or severing strip hereinabove mentioned, may be made of stiff paper, or card-board, or any other material suitable for the purposes of a severing means may be employed.

From the foregoing description of the present invention, it will be seen that a simply constructed envelop and a simple and efficient means is provided for accomplishing the objects of the invention, but, it will be understood, that while the elements herein described and shown in the accompanying drawings, are adapted to serve the purposes for which they are intended, it will be evident that they show merely one em-

bodiment of the principles of the invention. Hence, I do not limit my present invention 45 to the exact arrangements of the parts as described in the foregoing specification, nor do I confine myself to the exact details of the construction of the said parts as illustrated in the accompanying drawings. 50

I claim:—

1. An envelop comprising a main body, a lower flap, a sealing flap, and end flaps, said flaps being connected with the main body by narrow portions forming with the front and back of the envelop narrow squared or right-angled edge-sides, combined with a tearing strip secured upon the inner face of one of said edge-sides, said strip being of the same width as the edge-side to which it is secured 60 and having a portion extending from one end of said edge-side, substantially as and for the purposes set forth.

2. An envelop comprising a main body, a lower flap, a sealing flap, and end flaps, said flaps being connected with the main body by narrow portions forming with the front and back of the envelop narrow squared or right-angled edge-sides, one of said narrow portions being cut away to provide an opening 70 between said edge-side and the front and back of the envelop, and a tearing strip secured upon the inner face of the said edge-side, said tearing strip being of the same width as said edge-side, and the said tearing strip having one end-portion extending from said cut away part, substantially as and for the purposes set forth.

In testimony, that I claim the invention set forth above I have hereunto set my hand 80 this 26th day of September, 1914.

GEORGE P. FITZSIMMONS.
